UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR DRAFT-RIGGING.

1,273,907.

Specification of Letters Patent Patented July 30, 1918.

Application filed November 20, 1918. Serial No. 132,300.

To all whom it may concern:

Be it known that I, JOHN F. O'CONNOR, a citizen of the United States, residing at Chicago, in the county of Cook and State of Illinois, have invented a certain new and useful Improvement in Railway-Car Draft-Riggings, of which the following is a full, clear, concise, and exact description, reference being had to the accompanying drawings, forming a part of this specification.

This invention relates to improvements in railway car draft riggings.

One object of the invention is to provide a draft rigging having a yoke which remains stationary under buff and is provided with means for limiting the movement of the front follower.

Another object of the invention is to provide a yoke for draft rigging which is adapted to act as a limiting stop for the gear.

In the drawing forming a part of this specification, Figure 1 is a part horizontal section, part elevational view of a draft rigging showing my improvements in connection therewith. Fig. 2 is a transverse, vertical sectional view of the structure illustrated in Fig. 1 and taken on the line 2--2 thereof. Fig. 3 is a side elevation of one of the yoke members employed in my invention. And Figs. 4 and 5 are views corresponding respectively with Figs. 1 and 3 illustrating another embodiment of the invention.

Referring first to the construction illustrated in Figs. 1, 2, and 3, 10--10 denote center or draft sills to the inner faces of which are secured rear stops 11--11 and front stop members 12--12. Each of the latter is provided with a front stop shoulder 13 at its rear end and an auxiliary stop shoulder 14 at its front end, each stop member 12 having also upper and lower horizontal flanges 15 and 16 and an elongated centrally located slot 17 to accommodate the movements of the coupler key 18. The key 18 is adapted to connect the draw bar 19 with an improved two-part yoke designated generally by the reference A. As shown, the yoke A comprises two counter-part members each of which consists of an upper arm 20, lower arm 21, rear vertical connecting portion 22, front side plate 23 slotted as indicated at 24

and an intermediate vertical wall or partition 25, the latter being located as hereinabove described.

At its front end, each member of the yoke is provided with laterally extended shoulders 26 which are adapted to engage with said shoulders 14 and prevent rearward movement of the yoke, the normal position of the parts being as illustrated in Fig. 1. As clearly appears from the dotted lines in Fig. 1, the connecting side plates 23 of the yoke members are flared outwardly so as to permit radial movement of the draw bar as will be understood. Where the vertical posts 25 are located, the upper and lower walls 20 and 21 are extended outwardly as indicated at 27 so as to bring said posts 25 near the sills.

Located within the yoke A is illustrated a well known form of friction gear comprising a combined friction shell and spring casting 28, rear follower 29 and front follower 30, there being suitable friction elements 31 between the front follower and the friction shell. As appears from Figs. 1 and 2, the lower arm 21 of each yoke member is widened between the posts 25 and the front end of the yoke as indicated at 32 in Fig. 2 and upon which portions the front follower 30 is adapted to ride and be supported. The parts are held in proper position by means of a detachable saddle plate 33.

In operation, the yoke A remains stationary under buff due to the engagement of the shoulders 26 and 14. The draw bar moves inwardly relatively to the yoke and sills and thereby forces the front follower 30 rearwardly and actuates the friction gear. The vertical posts 25 of the yoke are so located with respect to the front follower that the latter will engage said posts 25 at the end of the permissible movement of the gear so that the yoke through the instrumentality of said posts 25 acts as a limiting stop in the operation of the gear. In draft, the front follower 30 remains stationary and the other parts of the gear are moved forwardly due to the key connection between the yoke and draw bar. This movement is continued until finally limited by the engagement of the posts 25 with the front follower 30. By making the yoke in two parts, the same may be readily assembled with the

friction shell and associated elements and the draw bar may be disconnected by merely removing the key 18.

In the form illustrated in Figs. 4 and 5, the arrangement of sills, rear stops, friction gear and front follower are the same as in the other figures. In this construction, however, the yoke A' which consists of two like parts, is provided with transversely extending upper and lower gibs 40-40 to engage the usual upper and lower shoulders of the draw bar 119, thus obviating the use of a coupler key. The front stops 112 are provided with front upper stop shoulders 113 and yoke stop shoulders 114, the latter co-operating with the laterally extending shoulders 126 on the two yoke members. In this arrangement, the yoke parts are somewhat similar to the yoke parts illustrated in the other figures except that the vertical intermediate posts 125 are somewhat longer than the posts 25. This is done so that the shoulders 41 on the friction shell casting will normally engage the rear vertical edges 42 of the posts 125. The forward edges 43 of said posts 125 are spaced from the front follower 130 the proper distance to limit the movement of the latter relatively to the gear.

The operation of the construction illustrated in Figs. 4 and 5 is similar to that illustrated in the other figures, but in draft, not only are the parts of the yoke A' limited in their forward movement by the follower 130, but the friction shell is also positively limited in its forward movement by the engagement of the shoulders 41 with the rear edges of the posts 125.

Although I have herein shown and described what I consider the preferred means

of carrying out the invention, the same are merely illustrative and I contemplate all changes that come within the scope of the claims appended hereto.

I claim:

1. As an article of manufacture a two-part yoke, each part being provided with a laterally extending shoulder at its front end, and a vertical post intermediate its ends, said posts being located in the rear of the front follower of a gear when the yoke is in service to thereby limit the movement of the follower rearwardly with respect thereto.

2. In a draft rigging, the combination with draft sills having front and rear stops secured thereto, of cushioning means including a front follower, a draw bar, and a yoke connected to said draw bar, said yoke having means co-operable with the front stops to prevent rearward movement of the yoke and provided also with posts intermediate its ends to limit the inward movement of the front follower.

3. In a draft rigging, the combination with draft sills having front and rear stops secured thereto, of a cushioning device including a front follower, and a two-part yoke for operatively connecting said device with a draw bar, each of said yoke parts having means co-operable with the front stops to prevent rearward movement of the yoke parts, each of said parts having also a vertical post located at the rear of the front follower and adapted to limit the rearward movement thereof.

In witness that I claim the foregoing I have hereunto subscribed my name this 16th day of Nov. 1916.

JOHN F. O'CONNOR.
